UNITED STATES PATENT OFFICE.

JAMES B. BARBEE, OF CENTRAL CITY, AND OTTO J. CROSS, OF NEDERLAND, COLORADO.

JIG.

1,328,778.

Specification of Letters Patent. Patented Jan. 20, 1920.

Application filed June 25, 1918. Serial No. 241,818.

To all whom it may concern:

Be it known that we, JAMES B. BARBEE and OTTO J. CROSS, citizens of the United States, residing at Central City and Nederland, in the counties of Gilpin and Boulder and State of Colorado, have invented certain new and useful Improvements in Jigs; and we do hereby declare the following to be a full, clear, and exact description of the invention, such as will enable others skilled in the art to which it appertains to make and use the same.

This invention relates to mills, and more particularly to jiggers. It is one of the objects of the present invention to greatly increase the operating capacity of that type of milling apparatus involving a shaking jig screen by which ore or pulp is segregated while immersed in water into portions of 20 different degrees of fineness and specific gravity.

Another object of the present invention is to provide an apparatus of this type which not only will have increased capacity in 25 the amount of ore treated in a given time, but will also be economical in the use of wash water, and furthermore it is an object to provide a machine of this type in which the parts in comparison to the amount 30 of material efficiently treated are of such dimensions as to permit the plant to be readily transported and easily erected or dismantled as may be required.

A further and important object of the 35 present invention is not only to provide for the separation of the valuable fine material from the ore pulp, separating it from the tailings, but also to provide for the continuous separation of "middlings" such for 40 instance as heavy particles of the pulp of such size as to be rejected by the screen, but of such weight as not to be carried away in the tailings.

With these and other objects in view, the 45 invention consists of the construction, the combination, and in details and arrangements of the parts more particularly herein- 50 after described relative to the preferred embodiment of the invention, as is illustrated in the accompanying drawing, in which:

Figure 1 is a vertical section longitudinally through the apparatus;

Fig. 2 is a plan view of the jig tank and screen, the operating mechanism being eliminated;

Fig. 3 is a cross section on lines 3—3 of Fig. 2 looking in the direction of the arrow; and

Fig. 4 is a cross section on line 4—4 of Fig. 2 looking in the direction of the arrow. 60 The apparatus consists of a tank 2 of any suitable material, proportion, design, and construction, which is divided by a partition 3 into two compartments, 2^a and 2^b, the latter of which is shown at 4 as provided with 65 an adjustable gate for regulating the level of the water in the tank. The compartment 2^a of the tank is shown clearly in Fig. 3 as being provided with communication directly into the lower part of an air chamber 70 2^c formed by a vertical longitudinal wall or partition and beneath a suitable ceiling or top portion 5, and in which air chamber air will be compressed or collected as the water level rises above the lower edge of the central wall of the compartment 2^a.

Mounted for shaking movement preferably comprising vertical components, in the compartment 2^a there is arranged a suitable screen box 6 having a screen bottom 7 of 80 any suitable mesh and construction, the rim of the box being connected by any suitable flexible diaphragm or other form of means to substantially close the top of the compartment 2^a so as to make it almost air-tight, the sealing means in the present instance being shown as a fabric strip 8 suitably attached to the adjacent top 5 and side and end walls of the compartment 2^a. The shaking jig screen box 6 is adapted to be 90 given its movement through any suitable form of mechanism, here shown as comprising a rock shaft 10 connected by links 11 to eccentrics 12 on an eccentric shaft 13, by which mechanism the screen is reciprocated, while pulp is fed into the box and on to the screen 7 by any suitable supply means. The tailings from the screen is floated off through a discharge launder 15 extending through an opening provided 100 therefor in the upper portion of the partition 3, the launder in the present instance discharging onto a device which is designed to carry away the solids of the tailings stream and thus remove the solids from the 105 water, which latter may be re-used with the minimum wastage by the operation of the tailings receiving device. This device is shown as comprising a receiver 16 in the form of a wheel rotated so as to carry the 110

collected solids upwardly and discharge them onto a tail trough 17 by which they may be conducted away from the jig.

To permit the free to-and-fro pulsation or surging of the water under the suction tendency created by the upward movement of the screen 7, the partition 3 is provided with a series of apertures 3^a which preferably are provided with screens to retard the movement of the suspended particles in the tailings compartments and likewise the values from the screen compartments.

One of the important features of this invention resides in the provision of means for collecting the middlings or that over-size portion of the pulp which collects on the screen 7 during the operation of the mill because it is too large to pass through the screen and too heavy to pass into the tailings launder 15. To that end we provide in the central portion of the screen an outlet plate 18 having an aperture 18^a and the size of which may be regulated by a shutter or valve 19. To the baffle or discharge plate 18 there is connected a hood 20, the bottom of which is open to receive a discharge pipe 21 having a gate valve 22 at its lower end. To prevent the discharge of the middlings or oversize particles into the compartment 2^a below the screen, a deflector or guard plate 23 is shown as attached to one side of the discharge plate 18 adjacent the opening thereof, this deflector 23 overhanging the mouth at the upper end of the discharge tube 21. At the end of the screen 7 adjacent the launder 15 there is also provided a fixed discharge plate 18 having an adjustable gate or valve member 19^b for regulating the rate of discharge or size of the aperture therefrom.

From the above general description of the apparatus, its operation may be briefly described as follows:

Pulp is fed into the screen box 6 while the latter is reciprocated and on the upward vertical movement of the screen there is created a suction in the water in the compartment 2^a so that there is a movement of the water from the compartment 2^b into the compartment 2^a and also from the air chamber 2^c downwardly so that on the downward stroke of the screen 7 the pulp is subjected to the upward rushing current of water and is therefore lifted to a considerably higher degree than would be the case if the screen compartment were freely open to the atmosphere. Conversely on the upward movement of the screen there is a strong downward action of the re-surging water which acts strongly to separate the finer particles and draw them through the screen. It will be seen therefore that through the present system the bed of pulp is more violently agitated than in forms of shaking screens in which the closed chamber is not employed.

Obviously, it will be necessary to vary the degree of air tension and pressure in the air chamber 2^c in accordance with the character of the material being treated, and to control this pressure the closed compartment of the tank is provided with suitable air valves 25 conveniently disposed for access by the operator.

What is claimed is:

1. A pulsating jigger comprising a water tank having a transverse partition forming at one end of the tank a tailings chamber, a longitudinal partition of less depth than the vertical depth of the tank in the plane of the partition, a cover forming with the partition and the tank walls an air chamber, a jiggling screen mounted in the tank along the other side of the partition and substantially at the top thereof, and having a discharge projecting into the tailings chamber, the transverse partition apertured to provide for equalization of water level between the several chambers, the motions of the screen pulsating the water between the air chamber and its own compartment to facilitate the treatment of the pulp.

2. A pulsating jigger comprising a water tank having a transverse partition forming at one end of the tank a tailings chamber, a longitudinal partition of less depth than the vertical depth of the tank in the plane of the partition, a cover forming with the partition and the tank walls an air chamber, a jiggling screen mounted in the tank along the other side of the partition and substantially at the top thereof, having a discharge projecting into the tailings chamber, the transverse partition apertured to provide for equalization of water level between the several chambers, the motions of the screen pulsating the water between the air chamber and its own compartment to facilitate the treatment of the pulp, and adjustable means for regulating the pulsations by changing the degree of compression of air in the air chamber.

3. In an apparatus of the character described, a tank having a tailings chamber at one end, and longitudinally extending parallel compartments each of which is substantially sealed at its top, one by a cover and the other by a vertically movable jiggling screen, the parallel compartments separated by a partition extending from the top of the tank downward and terminating short of the bottom of the tank so that water will pulsate, when the screen is reciprocated, to and from the adjacent compartment and compress air therein, and means providing for the substantial equalization of the water level in the several chambers.

In testimony whereof we affix our signatures.

JAMES B. BARBEE,
OTTO J. CROSS.
